UNITED STATES PATENT OFFICE.

GEORGE F. STEPHENSON, OF LUZERNE, PENNSYLVANIA.

FIRE-EXTINGUISHER.

1,217,236.

Specification of Letters Patent. Patented Feb. 27, 1917.

Application filed May 26, 1916. Serial No. 100,047.

To all whom it may concern:

Be it known that I, GEORGE F. STEPHENSON, a citizen of the United States, residing at Luzerne, Luzerne county, Pennsylvania, have invented new and useful Improvements 5 in Fire-Extinguishers, of which the following is a specification.

My invention relates particularly to automatic fire extinguishers, and is designed for 10 use in buildings, vehicles or wherever such devices are necessary.

It is common to provide automatic fire extinguishers containing an inert chemical, as a liquid solution of bicarbonate of soda, 15 and to provide a separate acid container, the contents of which is adapted to be mixed with the chemical to generate gas, which forces the combined liquid through a discharge pipe onto the fire.

20 But this combined chemical is very corrosive, eating into fabrics, pitting and rusting metals, and destroying or damaging everything with which it contacts, thereby materially increasing the loss occasioned by 25 the fire.

The simplicity of parts, ease of operation, and efficiency of power generated by this 30 class of extinguishers is, however, unquestionable, and therefore, one object of my invention is the provision of an automatic fire extinguisher, wherein the generation of pressure by the automatic commingling of an acid with an inert chemical, is employed 35 to discharge a fire extinguishing compound harmless to fabrics, metals or other materials, animal or vegetable, whereby any loss occasioned by a fire is not increased by damages caused by the chemical extinguishing compound.

40 To this end, I have contrived a mechanism wherein the fire extinguishing liquid and the pressure generating chemicals are kept separate, the gas pressure only being admitted to the reservoir containing the fire extinguishing compound to discharge the latter.

Another object of my invention is the provision of novel and improved means for supporting the acid container in place against accidentally commingling with the normally inert chemical, and for insuring the 50 automatic emptying or discharge of the acid container when necessary.

A further object is to provide a simple support and releasing means for the acid container, which permits the ready removal and replacement of such container.

Other objects and advantages will be more fully disclosed hereinafter and particularly pointed out in the claims.

In the drawings.

Figure 1 is a side view of an automobile equipped with one embodiment of my invention;

Fig. 2 is a sectional view of my invention;

Fig. 3 is a detail top plan view of the support for the acid container, as it normally appears when set for operation;

Fig. 4 is a sectional view thereof, showing the acid bottle or container in place;

Fig. 5 is a bottom plan view of the container support, showing the container in cross-section;

Fig. 6 is a top plan view of the container support, showing the positions of the parts when tripped;

Fig. 7 is a sectional view, showing the bottle in the position assumed just as it is released;

Fig. 8 is a bottom plan of the parts released, the container being shown in cross section;

Fig. 9 is a front view of the valve normally closing communication between the reservoir and the pressure chamber;

Fig. 10 is a detail of the fusible lock which retains the container support effective, and

Fig. 11 is a cross sectional view of a sprinkler head.

Although I have elected to illustrate the device as applied to an automobile, it is understood that my invention is not restricted in its use thereto.

However, it is especially adapted for this and kindred uses, by reason of its compactness, which enables it to be readily applied to vehicles of this description. Damage and loss due to backfiring in the carburetors of automobiles is of frequent occurrence, and the operator oftentimes is unaware of the fire until it has obtained considerable headway, after which it is too dangerous to attempt to extinguish the blaze. As the fire starts beneath the hood inclosing the motor, it heats the hood to such a high degree that the operator when finally apprised of the danger, is unable to raise the hood in order to obtain access to the blaze, without severely burning himself.

My invention is preferably attached to the front of the dashboard underneath the hood, in position for immediate automatic opera-

tion as soon as the fire starts, and without attention of any sort on the part of the operator.

The location of the device in the zone of the fire obviates the necessity of the operator taking any risks, and in fact, extinguishes the blaze before it can do any appreciable amount of damage, and often before the operator is aware of such condition.

Referring to Fig. 1, the motor or engine 1 located between the radiator 2 and the dashboard 3, is completely inclosed by a hood 4. A brace rod 5 above the motor, connects the radiator and dashboard.

The reservoir 6 containing any suitable harmless fire extinguishing liquid is conveniently secured to the front of the dashboard 3 beneath the hood 4 in any suitable manner, as by straps 7. So far as the purposes of this invention are concerned, the reservoir may be considered as being filled with water, although any suitable fire extinguishing liquid may be employed. A flexible discharge tube 8 leads from the reservoir to a sprinkler head 9, (see Figs. 1 and 11) located preferably a little in front of and above the carburetor 10. A hanger 11 conveniently secures the tube to the brace rod 5.

The reservoir may be separate from the power-generating chamber 12, but in the embodiment herein shown, (Fig. 2) and in order to render the device more compact, I combine the reservoir and the power-generating or pressure chamber in one vessel or tank, preferably cylindrical in shape, a partition 13 separating the interior into two compartments, the larger of which contains the fire extinguishing liquid and the smaller containing a normally inert chemical adapted, when an acid is commingled therewith, to generate a large volume of gas.

The fire extinguishing liquid may be introduced into the reservoir through an opening therein, closed by a screw plug 14.

It will also be noted that the inlet end of the discharge tube 8 extends to a point close to the bottom of the reservoir to enable practically the entire contents thereof to be discharged. A union 15 enables the ready attachment and disconnection of that portion of the tube which is exterior of the reservoir to and from that portion which extends into the reservoir through the packing gland 16.

The inert chemical, as a liquid solution of bicarbonate of soda, for example, is introduced into the pressure chamber through a threaded nipple 17 communicating therewith, on which is screwed a cap or plug 18.

The acid is held in a receptacle 23 apart from the inert chemical, and there must be no accidental commingling of the acid and chemical. This necessitates the provision of means for securely sealing the acid container.

On the other hand, means must be provided to effect the instantaneous and automatic mixture of the acid with the chemical upon the occurrence of a blaze or of a dangerous degree of heat, which requires that the closure for the acid container be readily disabled, and the contents of the receptacle distributed in the normally inert chemical solution.

Furthermore, it is desirable that the acid be renewed from time to time in order to preserve its strength and insure the generation of a large volume of gas. This necessitates that the acid container be readily accessible to permit its removal and replacement, and also, that the automatic acid-releasing means be of a simple character to enable the operator to spring it when removing the acid container, and reset it when replacing the container, without damage. As the acid used is often dangerous to handle, and its action when mixed with the inert chemical, practically instantaneous, I have contrived a supporting and releasing means which meets every condition of safety, instant action, simplicity and accessibility.

The cap or plug 18 (Figs. 2 to 8) is preferably recessed on its inner face, as at 19, (Fig. 4), a sealing disk or closure 20 being seated therein. A flange or bracket 21 is fastened to the inner face of the cap adjacent the recess, the free end of the bracket extending partially across the recess and being inclined downwardly therefrom to coact with a clamping member 22 in sustaining the acid container 23.

This angular clamping member 22 passes through, and is swiveled in the cap at a point substantially opposite the bracket. The inner end of this member comprises an arm or finger 24, which may be slightly curved (see Figs. 3 and 5) as is the free edge of the bracket or flange 21. The acid receptacle 23 is generally a glass bottle or vial, the neck of which, in the present instance, is outwardly beveled or flared, as at 25, the inclination of the bracket conforming thereto. The mouth 26 of the acid bottle enters the recess 19 and is closed by the seal 20, the inclined bracket contacting with the beveled neck portion 25 on one side, and the arm or finger 24 contacting with and conforming to the curvature of the beveled portion of the neck at a point opposite the bracket to support the acid receptacle. The outer end of the clamping member comprises an arm 27 extending across a recess 28 in the outer face of the cap and offset or bent in the same plane, the offset end terminating in a hook 29. The clamping member 22 is resilient, and after the bottle 23 has been placed in the position shown in Fig. 4, the arm 27 is swung from its release position, shown in Fig. 6, to its effective position, shown in Fig. 3, whereby

- to press the clamping finger 24 snugly against the beveled neck of the acid container, at which time the hooked end 29 of the outer arm has passed between a pair of 5 posts 30 fastened in the outer face of the cap 18, whereupon a pin or bolt 31 is inserted between the hook 29 and the posts (see Fig. 10) to hold the clamp in effective position.
- 10 The arm or finger 24 exerts a pressure against the beveled neck of the container 23 which forces or crowds the mouth of the container against the seal 20 to absolutely prevent the entrance of the inert chemical 15 to the acid receptacle, due to any shaking or change in position of the vessel, 6, 12. At the same time, there is no danger of breaking the glass bottle on account of such pressure, because of the resiliency of the 20 clamp.
- The bolt 31 is preferably recessed as at 32 (Fig. 10) to fit over the posts 30 which prevents accidental endwise displacement of the bolt. The upper ends of the posts 30 25 are bent over, as at 33, and cooperate with the hooked end 29 of the clamping member to prevent lateral displacement of the bolt or pin 31.
- A spring 34, seated for protection against 30 injury, in the recess 28 on the outer face of the cap, exerts its tension against the arm 27 to shift the clamp to idle position (Fig. 6), but is normally restrained from operation by the engagement of the bolt 31 and 35 posts 30, the spring, by its pressure, aiding in maintaining the bolt effective against accidentally jarring out of place, by taking up all looseness.
- It will be seen that the acid container 23 40 may be readily applied to the cap 18, the clamping arm 24 tensioned to coact with the bracket 21 in holding the bottle in sealed position, and the bolt 31 slipped into place between the hooked end 29 of the outer arm 45 27 of the clamping member and the posts 30, after which the cap may be screwed onto the nipple.
- The removal of the acid receptacle is as 50 easily accomplished by first unscrewing and removing the cap, and then pressing the outer arm 27 to shift its hooked end 29 away from the posts 30, in a direction to release the bolt 31, after the removal of which, the arm 27 may be slowly released 55 against its own resiliency and the tension of the spring 34 until the clamping arm 24 releases the bottle, which may then be removed, emptied, refilled and replaced as above explained.
- 60 The automatic release of the acid receptacle 23 is effected by making the bolt or pin 31 of fusible material. Thus, upon the occurrence of a blaze or a dangerous degree of heat, adjacent the fuse, the latter breaks, 65 freeing the arm 27 to the action of the
- spring 34, which shifts the clamping arm 24 to release the bottle or receptacle (Figs. 6 to 8). As the extent of contact of the flange 21 with the neck of the bottle is much less than half the circumference of the neck, 70 the bracket alone is insufficient to support the bottle when the clamp is disabled. Hence, the bottle, due to the weight of the liquid therein, slips off the inclined bracket 21 and is submerged in the inert chemical 75 in the pressure chamber 12.
- A float or cork 35 fastened to one side of the bottom of the bottle as by a strap 36, tends to invert the bottle when it is freed from the clamp, to insure the rapid dissemination of its contents throughout the inert 80 chemical.
- Such mixture of the acid and chemical immediately generates a large volume of gas in the pressure chamber 12. 85
- Heretofore, this gas pressure was utilized to discharge the commingled liquid itself onto the fire zone, but this liquid is ruinous to fabrics, or metals, and consequently I utilize the gas pressure only to force any suitable harmless fire extinguishing liquid 90 through the discharge tube 8, and sprinkler head 9.
- This pressure may be conducted to the reservoir 6 above the liquid level therein, in 95 any suitable manner, but as one simple means to admit the gas to the reservoir and prevent the gas-generating liquid from entering the reservoir, I provide the partition 13 with an opening 37 (Figs. 2 and 9) located well 100 above the liquid level in the two compartments, which opening is normally closed by a valve 38 resting against a gasket 39 surrounding the opening. This valve is made self-adjusting and universally tiltable by being supported at its center by a spring 40, which also holds the valve to its seat and enables it to adjust itself to any inequalities 105 therein.
- The gas pressure within the chemical 110 chamber 12 forces the valve 38 from its seat and enters the reservoir above the liquid level therein, but the gas generating chemicals cannot enter the reservoir because of the inaccessibility of the opening 37. 115
- It will be obvious that my invention is embodied in a simple, inexpensive device readily installed and adapted to be used over and over again, there being no parts to wear out, or accidentally get out of order. The 120 only part necessary to replace is the fusible bolt 31, the cost of which is negligible.
- Changes may be made in the form and arrangement of the several features without departing from the spirit and scope of the 125 invention.
- What I claim as new, is:—
1. The combination in an automatic fire extinguisher, with a pressure chamber containing a normally inert liquid, of an acid 130

5 container within the chamber, having an open mouth and an inclined portion; a closure adjacent the open mouth of the container; a resilient clamp to releasably engage the inclined portion of the container and press the open mouth thereof against the closure; and means to automatically release the clamp.

10 2. The combination in an automatic fire extinguisher; of an acid container having a flaring portion, and an open mouth; a closure adjacent the open mouth; a rigid inclined bracket engaged by the flaring portion; a resilient clamp in contact with the 15 flaring portion at a point substantially opposite the bracket to coöperate with the latter in supporting the container, and to press the open mouth of the container against the closure; and means to automatically disable 20 the clamp, to enable the container to free itself from the bracket.

25 3. The combination in an automatic fire extinguisher; of a container having a flaring portion, and an open mouth; a bracket engaged by one side of the container, the bracket alone being insufficient to support the container; a clamp to contact with the flaring portion substantially opposite the bracket to coact therewith in supporting the 30 container; and means to automatically disable the clamp.

35 4. The combination in an automatic fire extinguisher; of a container; a shiftable clamp to releasably retain the container in normal position, the clamp including an arm having a hook; means tending to shift the clamp in one direction to effect the release of the container; posts between which the arm projects; and a fusible bolt interposed 40 between the posts and the hooked portion of the arm to lock the clamp in effective position.

45 5. The combination in an automatic fire extinguisher; of a container; a shiftable clamp to releasably retain the container in normal position, the clamp including an arm having a hook; means tending to shift the clamp in one direction to effect the release of the container; posts between which the arm projects; and a fusible bolt interposed 50 between the posts and the hooked portion of the arm to lock the clamp in effective position, the posts being hooked to prevent accidental displacement of the bolt.

55 6. The combination in an automatic fire extinguisher; of a container; a shiftable clamp to releasably retain the container in normal position, the clamp including an arm having a hook; means tending to shift the clamp in one direction to effect the release of the container; posts between which the arm projects; and a fusible bolt interposed 60 between the posts and the hooked portion of the arm to lock the clamp in effective position, the bolt being recessed to fit

against the posts to prevent accidental endwise displacement of the bolt.

7. The combination with an automatic fire extinguisher having a pressure chamber containing a normally inert liquid, the chamber having an opening therein; of a cap removably closing the opening; a separate acid container; a rigid bracket on the inner face of the cap; a clamp swiveled in the cap; the acid container held between the bracket and clamp; and means to effect the automatic release of the clamp.

10 8. The combination with an automatic fire extinguisher having a pressure chamber containing a normally inert liquid, and provided with an opening; of a cap to removably close the opening; a separate acid container, having a flaring portion; a rigid bracket on the inner face of the cap, engaged by the container; a clamp swiveled in the cap and having an arm to engage the flaring portion of the container substantially opposite the bracket; means normally tending to disengage the clamp from the container; and fusible locking means to retain the 35 clamp effective.

20 9. The combination with an automatic fire extinguisher having a pressure chamber containing a normally inert liquid, and provided with an opening; of a cap to removably close the opening, the cap being recessed on both its inner and outer faces; a sealing disk within the inner recess; an acid container having an open mouth entered in the inner recess; a bracket adjacent the inner recess, engaged by the container; a resilient clamp, angular in shape, and shiftably mounted in the cap, one arm of the clamp adapted to engage the container at a point substantially opposite the bracket 100 to coöperate with the bracket in supporting the container firmly in place; the remaining arm of the clamp extending across the outer recess in the cap; means seated in the outer recess tending to shift the clamp to inoperative 105 position to release the container; and a fusible lock to retain the clamp effective.

10. In an automatic fire extinguisher, the combination of a container having an open mouth; a removable closure having a recess entered by the open mouth of the container; a sloping bracket to contact one side of the container and insufficient alone to support the container; a clamp to contact the container at a point substantially opposite the 110 bracket, to coact therewith in supporting the container; and means to release the clamp.

11. In an automatic fire extinguisher, the combination with a pressure chamber; and a receptacle whose contents must normally be separate from the contents of the pressure chamber; of a self contained support and release for the receptacle, comprising a cap removably fitted into the wall of the 120

pressure chamber; permanent and shiftable supports coating to secure the receptacle to the cap against leakage; a manually-removable heat-affected lock to hold the shiftable support effective, and a spring to disable the shiftable support upon the failure of the lock.

12. An automatic fire extinguisher comprising a fluid reservoir; a pressure chamber containing an inert chemical and having a communication with the reservoir located above the level of the inert chemical; a spring-pressed valve normally closing such communication and opened by pressure from the pressure chamber; an acid container within the pressure chamber; releasable means to normally support the acid container with its contents intact; a fusible lock to hold the releasable supporting means effective and a discharge pipe leading from the reservoir.

13. An automatic fire extinguisher comprising a fluid reservoir; a pressure chamber containing an inert chemical and having a communication with the reservoir located above the level of the inert chemical; a spring-pressed valve normally closing such communication and opened by pressure from the pressure chamber; an acid container within the pressure chamber; means to support the acid container with its contents intact, such means tending to release the container; a locking device adapted to be disabled by an undue degree of heat, to permit the automatic release of the container by its supporting means; and a discharge pipe leading from the container.

14. An automatic fire extinguisher comprising a liquid reservoir; a pressure generating chamber containing a normally inert chemical, in communication therewith; an

acid container; automatically releasable means to normally support the container; a fuse to hold the supporting means effective; a spring-pressed universally tiltable valve in the communication between the reservoir and chamber adapted to be displaced by pressure within the chamber; and a discharge pipe leading from the reservoir.

15. In an automatic fire extinguisher, the combination with a pressure chamber, having a normally inert chemical introduced through an opening therein; of a removable cap to close the opening; an acid container; means carried by the cap and extending therethrough into the pressure chamber to releasably secure the acid container to the cap; and fusible means mounted on the cap exteriorly thereof to coöperate with the outer portion of the container-securing means to lock it in effective position, and so maintain it, while removing the cap and container from and applying it to the chamber.

16. In an automatic fire extinguisher, the combination with a pressure chamber, having a normally inert chemical introduced through an opening therein; and an acid container, the contents of which is adapted to be commingled with the inert chemical; of a self-contained combined support for the acid container, closure for the opening, and support-disabling means, comprising a cap removably secured in the opening; a holding means mounted in the cap and extending into the pressure chamber to releasably secure the acid container to the cap; and fusible means carried by the cap exteriorly thereof, to engage the outer portion of the holding means and lock it in effective position.

GEORGE F. STEPHENSON.
